HANDLE FOR CUTLERY.

No. 20,252.

Patented Nov. 4, 1890.

UNITED STATES PATENT OFFICE.

HARRY P. FAIRCHILD, OF NEW YORK, N. Y.

DESIGN FOR A HANDLE FOR CUTLERY.

SPECIFICATION forming part of Design No. 20,252, dated November 4, 1890.

Application filed October 2, 1890. Serial No. 366,889. Term of patent 7 years.

To all whom it may concern:

Be it known that I, HARRY P. FAIRCHILD, a citizen of the United States, residing at New York, in the county of New York and State 5 of New York, have invented a new Design for a Handle for Cutlery, &c., of which the following is a specification.

My invention consists of a design for a handle to be used on buttoners, nail-files, knives, 10 forks, spoons, or any similar article requiring a handle.

The nature of my design is fully represented by the accompanying cut or print, to which reference is hereby made.

I claim as my invention—

The design for a handle hereunto annexed

In witness whereof I hereunto set my hand in the presence of two witnesses.

HARRY P. FAIRCHILD.
